CLAIM

We claim the ornamental design for a desktop fish tank, as shown and described.

DESCRIPTION

FIG. 1 is a front view of a desktop fish tank.

FIG. 2 is a rear view of the desktop fish tank.

FIG. 3 is a left view of the desktop fish tank.

FIG. 4 is a right view of the desktop fish tank.

FIG. 5 is a top view of the desktop fish tank.

FIG. 6 is a bottom view of the desktop fish tank.

FIG. 7 is a perspective view of the desktop fish tank; and, FIG. 8 is another perspective view with the lid open of a desktop fish tank.

The broken lines depicted in the drawings represent unclaimed portions of the article and form no part of the claimed design.
